PRINTING CYLINDER STRIPPING MEANS WITH STOP PRESS CONTROL

William B. Leavens, Jr., West Orange, N. J.

Application February 15, 1955, Serial No. 488,271

10 Claims. (Cl. 101—232)

This invention relates to improvements in printing presses, and has reference, more particularly, to mechanism for separating printed material from a printing cylinder of a printing press to assist normal discharge thereof, but operative to stop the press in event of abnormal discharge thereof.

In the operation of a rotary printing press generally, and especially when the printing is done with tacky inks and varnishes, there is tendency of the printed material to adhere to a printing cylinder so as to detrimentally interfere with normal discharge of said material from the latter. This is not only undesirable with respect to rotary printing presses regardless of type, but with respect to special purpose presses may render operation thereof impractical if tacky inks and varnishes are used. For example, in the production of paper boxes and cartons, automatic machines are available which diecut the boxes or cartons from a web of cardboard fed into the machine, then cut the web into sheets, and thereupon print the box or carton blanks contained in the sheets, all in a continuous sequence of these operations. One of the principal limitations in the use of machines of the latter character is the fact that the printing operation must be carried out with inks which are substantially non-tacky, whereby to avoid risk of adherence of the printed sheet to a printing cylinder, and thus to assure normal issue of the printed sheet from the latter. Owing to this limitation, such automatic machines have heretofore been operated with difficulty when the printing operation required use of tacky inks and varnishes now generally demanded by box and carton consumers.

Having the above in view, it is an object of this invention to provide mechanism which normally functions to peel or strip printed material away from the surface of a printing cylinder, especially under conditions involving the use of tacky inks and varnishes for the printing operation.

Another object of this invention is to provide mechanism for separating printed material from the printing plate or plates of a printing cylinder, whereby to assist normal discharge of said printed material therefrom; said mechanism being adapted to yield to pressure of abnormally discharged material, which otherwise would jam so as to both risk injury to the printing plates and cause destruction and waste of printed material; said mechanism being cooperative with means to control operation of the printing press, whereby, when yielding to jamming material, to immediately effect stoppage of the operation of the press.

The above and other objects will be understood from a reading of the following detailed description of this invention in connection with the accompanying drawings, in which:

Fig. 1 is an elevational view showing the peeling or stripping mechanism of this invention in operative relation to a printing cylinder, the carrying rolls, which receive printed material discharged from the latter, being omitted.

Fig. 2 is a cross-sectional view, taken on line 2—2 in Fig. 1, this view including the carrying rolls which receive the printed material discharged from the printing cylinder.

Fig. 3 is a fragmentary horizontal sectional view, taken on line 3—3 in Fig. 2.

2

Fig. 4 is a diagrammatic view showing a preferred formation of the tip end portion of a peeler blade as operatively related to the printing cylinder and printing plates mounted thereon.

5 Fig. 5 is a fragmentary cross-sectional view, similar to that of Fig. 2, but showing a modified construction and arrangement of the peeling and stripping mechanism of this invention.

Referring to the drawings, wherein like characters of 10 reference are employed to indicate corresponding parts, the reference character 10 indicates the side frames of a printing press. Journaled in and between said side frames is the shaft 11 of a printing cylinder 12, upon the peripheral surface of which one or more printing plates 13 are mounted. Journaled in and between the side frames 10, beneath the printing cylinder 12, for cooperation therewith, is a bed roll 14. Said printing cylinder and bed roll are driven by power transmission means (not shown) in any suitable manner known to the art.

20 A preferred embodiment of the peeling or stripping mechanism according to this invention, as shown in Figs. 1 to 4 inclusive, comprises a bridge plate 15 which is disposed to extend across the outer face of the printing cylinder 12 in concentric outwardly offset relation thereto, and parallel to the axis thereof. Said bridge plate 15 is movably supported by and between swingable carrier members 16, which are pivoted on the shaft 11 of the printing cylinder 12, intermediate the ends of the latter and the press side frames 10, for outward extension from said shaft. Suitable means is provided for uniting the bridge plate with the carrier members 16, and to this end, said carrier members are preferably provided, on their inner faces, with ribs 17 to which the ends of the bridge bar are suitably secured. Extending outwardly 25 from the free ends of the carrier members 16, preferably in line with the top margins thereof, and as unitary parts thereof, are extension arms 18. These extension arms 18 are provided with angular stop fingers 19 which overhang shoulder portions 20 formed in connection with 30 the side frames 10 of the press. Fixed on said shoulder portions 20, to upstand therefrom, are stop posts or pins 21 which are normally abutted by said stop fingers 19, thereby limiting down-swinging movement of the carrier members 16, and thus disposing the bridge plate 15 in a 35 normal arrested position above and relative to the plane of outward movement of printed material issuing from the printing cylinder 12, such plane being ordinarily referred to as the paper line.

40 Fixed on the outer face of the bridge plate 15, to extend longitudinally therewith, is a coupling bar 22, which is preferably of key-stone shape in cross-section so as to possess undercut top and bottom edges. Adjustably supported by said coupling bar 22, to depend from the bridge plate 15 toward the paper line of the press, and adjacently 45 contiguous to the printing cylinder 12 and the faces of the printing plates 13 thereon, are a plurality of suitably spaced apart peeling or stripping devices. Each peeling or stripping device comprises a preferably arcuate peeler or stripper blade 23 which depends from a coupler block 50 24, formed to provide, in the rear side thereof, a transverse channel 25 to receive the coupling bar 22 when said coupler block is engaged thereover. Means is provided to detachably secure the coupler block 24 to the coupling bar 22. Illustrative of one form of means for this purpose, one side wall, preferably the bottom wall, of said channel 25 is shaped to conform to the undercut bottom edge of the coupling bar 22. Disposed within the channel 55 25 of the coupling block 24 is a keeper wedge piece 26, the bottom side of which is shaped to conform to the undercut upper edge of the coupling bar 22, and the upper side of which is shaped to conform to the opposite or top side wall of the channel 25 of the coupling block 24.

To lock the coupler block in a selected adjusted position along and in connection with the bridge plate 15, a draw screw or bolt 7 is passed through the coupler block to screw into the keeper wedge piece 26, so that, when turned home, it will draw the latter into holding engagement with the coupling bar 22, whereby to clamp the coupler block thereto, and thus retain the peeler or stripper blade 23, which depends from the latter, in a desired position relative to and intermediate the ends of the printing cylinder 12 and the printing plates thereon.

Ordinarily carrying roll means is provided outwardly offset from the printing cylinder 12 and bed roll 14, and is adapted to receive a printed sheet S as it issues therefrom, so as to carry said sheet onward for discharge or delivery to other mechanism, as the case may be. Illustratively, said carrying roll means comprises a lower roll 8, the shaft 29 of which is journaled in and between the press side frames 10. Co-operative with said lower roll is an upper roll comprising spaced gripper disks 30 fixed on a shaft 31. Said upper roll is preferably removable from the press, and, in such case, the shaft 31 is journaled in and between bearings 32, which are removably supported by socketed brackets 33 with which the press side frames 10 are provided.

Each peeler or stripper blade 23 is provided with an arcuate outer edge profile 34 which is substantially concentric to the pivotal fulcrum of the bridge plate carrier members 16, so that upon upward swing of the peeling or stripping mechanism, under circumstances hereinafter set forth, the peeler or stripper blades will clear the shaft 31 of the upper carrying roll. Each peeler or stripper blade is also provided with an arcuate inner edge profile 35 somewhat eccentric to the pivotal fulcrum of the bridge plate carrier members 16, whereby to diverge upwardly from its free end, relative to the opposed periphery of the printing cylinder and printing plates thereon, toward its juncture with the bottom edge portion of the bridge plate 15, so as to provide, at said juncture, an internal stop shoulder 36 which a printed sheet S, issuing from the printing cylinder, that may accidentally escape the peeling or stripping action of the blade, will engage and exert lifting pressure against the peeling and stripping mechanism for purposes presently to be described. Each peeler or stripper blade terminates at its free end in a bottom edge 37 which is disposed in plane substantially parallel to and adjacently above the paper line. The intersecting inner and bottom edges 35-37 of the blade define a tip portion which underlies the printing cylinder and its printing plates, and which is inwardly directed toward and so as to terminate adjacent to the nip of the latter with the bed roll 14.

The shape of the tip portion of a peeler or stripper blade 23 is subject to variation, but a preferred formation thereof, which possesses desirable characteristics, is shown. In such form, the bottom edge 37, as it approaches the tip extremity, is provided with an upwardly inclined section 38, preferably at an angle divergent to the plane of the paper line of approximately 5°. The tip portion is provided with a rearwardly and upwardly inclined top edge 39, which leads to a rearwardly and relatively downwardly extending section 40 that intersects the inner edge 35 of the blade. Due to such top formation of the tip portion, the sharp extremity is directed away from the surfaces of the printing plates 13 mounted on the printing cylinder 12, and the juncture of sections 39 and 40 of said top formation provides means for fending the sharp extremity of the tip away from printing plate surfaces, so that injurious plowing or digging of said tip extremity into the latter is avoided, in event a blade should be accidentally or momentarily sprung toward the same.

Mounted on one of the shoulder portions 20 of the press side frames 10 is an electric switch 41 having an actuating button 42. Said switch 41 is electrically connected, through suitable circuits and control agencies (not shown) with the press drive motor. The extension arm 18 of an

adjacent carrier member 16 of the peeling and stripping mechanism is provided with an angular switch control finger 43 which overhangs and presses down upon the switch control button 42, whereby to hold the switch 41 closed, and the press drive motor operative, so long as the peeling or stripping mechanism remains in normal cooperative relation to the printing cylinder 12.

In the operation of the above described embodiment of the peeling and stripping mechanism, as a printed sheet 10 S issues from the printing cylinder 12, its leading edge portion, as normally advanced, will pass under the tip portions of the peeler or stripper blades 23, so as to be engaged beneath the bottom edges 37 thereof. Preferably the bottom edges 37 and 38 of the blades 23 are of V-shape in cross-section as shown, so that the sheet material contact thereof is reduced to a minimum. When a printed sheet S is advanced beneath the peeler or stripper blades, the sheet will be held down thereby, and thus compelled to separate from the surface of a printing plate 13 by 20 which it is printed, so that any tendency to adhere to the latter is overcome, especially when the printing is done with tacky ink or with varnish. In laying out jobs to be printed, effort is made to so arrange the disposition of imprints that leading edge portions of the sheet, or leading edge portions of individual diecut box blanks contained in the sheet, are not printed, and are thus free from tacky ink or varnish. Since such leading edge portions first issue from the printing cylinder, and being unprinted and therefore non-tacky, the same, when emerging 30 from the nip of a printing cylinder carried printing plate 13 and the bed roll 14, tend to spring away from the printing plate surface so as to project tangentially therefrom. By reason of this, such leading edge portions will be disposed to normally pass beneath the tip portions of 35 the peeler or stripper blades, so as to be operatively engaged by said blades for desired peeling or stripping effect thereof.

In the operation of the press there is possibility that something may happen to the printed sheet S, or some 40 accidental deformation thereof may occur, which allows its leading edge portion, or the leading edge portion of one or more of its contained diecut box blanks, to escape and pass over the tip portion of one or more peeler or stripper blades, with the result that the issuing printed sheet S 45 passes upwardly between the printing cylinder and the inner edges 35 of the peeler or stripper blade or blades. In such case the sheet will be moved upwardly until it abuts the stop shoulder 36 provided in connection with the bridge plate 15, thereupon being operative to exert an 50 upward thrust against the peeling and stripping mechanism. Under such exerted upthrust, the carrier members 16 are upswung about their pivotal connections with the printing cylinder shaft 11, thereby also upswinging the extension arms 18 and their stop fingers 19 away from 55 stopped engagement with the stop posts or pins 21. To counterbalance the weight of the peeling or stripping mechanism, whereby to render said mechanism readily responsive and less resistant to such upswinging movement thereof, compression springs 44 are mounted around 60 the stop posts or pins 21 intermediate the press side frame shoulder portions 20 and the stop fingers 19. Similarly, if for any reason the printed sheet S issuing from the printing cylinder should buckle, crumple or otherwise become deformed after entering beneath the peeler or 65 stripper blades 23, thereby creating a jam, the resulting jamming accumulation will also exert upswinging thrust upon the peeling or stripping mechanism. In any case, the upswinging movement of the peeling or stripping mechanism withdraws the switch control finger 43 from the 70 actuating button 42 of switch 41, whereby to immediately allow the switch to open, and thus to interrupt service of power to the press drive motor, so as to at once automatically stop the press. Such prompt stopping of the 75 press prevents undue waste of printed material, and avoids

risk of injury by jamming material to printing plate surfaces.

Upon occurrence of a jam of printed material and resultant stopping of the press, the peeling or stripping mechanism can be manually upswung out of the way, and, if necessary, the upper carrying roll can be removed, thus giving convenient access to the jamming material, so that the same may be quickly removed and cleared away and the press restarted with minimum time loss in operation thereof.

Referring to Fig. 5, there is shown therein a modified form of the peeling or stripping mechanism which, however, embodies the general principles of construction and mode of operation according to this invention. The main difference between this modified form and the hereinabove previously described form involves the means for supporting the bridge plate by which the peeler or stripper blades are carried. In said modified form, the bridge plate 15' is of flat instead of arcuate formation, and is slidably supported by its ends in upwardly and outwardly inclined channeled slideway guides 45, which are affixed to the inner faces of the press side frames 10. The bridge plate 15' is provided at its top portion, for extension from respective ends thereof, with stop fingers 19', to abut the stop posts or pins 21, and at one end with a switch control finger 43' to actuate the switch button 42 of the switch 41. The peeler or stripper blades 23 are mounted on the bridge plate 15' in the manner previously described. This modified embodiment of the invention is best adapted for use in cases wherein the arrangement of the printing plates 13 on the printing cylinder 12 permits the latter to be provided with annular channels 46 intermediate printing plates; said channels affording clearance for the peeler or stripper blade tip portions to accomodate movement thereof under upthrusting pressure exerted against the same or against the bridge plate.

It will be understood that the illustrative embodiments of this invention shown in the drawings and herein described can be variously modified as to details thereof without departing from the principles of this invention within the scope of the herefollowing claims.

Having now described my invention, I claim:

1. In a printing press the combination with a printing cylinder thereof of stripping means adjacent the discharge side of the printing cylinder including peeler blade means to engage the leading end of printed material issuing from said printing cylinder, whereby to inhibit adherence of said material to the latter and thus normally compelling said material to advance along the plane of the paper line of the press, and means to pivotally support said stripping means for movement in a path substantially concentric to the axis of said printing cylinder, whereby the same will yield to upthrusting pressure of printed material abnormally discharged from the printing cylinder with jamming effect, and whereby said stripping means can be manually displaced to give access to jamming material for removal thereof.

2. In a printing press the combination with a printing cylinder thereof of stripping means adjacent the discharge side of the printing cylinder including peeler blade means to engage the leading end of printed material issuing from said printing cylinder, whereby to inhibit adherence of said material to the latter and thus normally compelling said material to advance along the plane of the paper line of the press, means to movably support said stripping means whereby the same can yield to up-thrusting pressure of printed material abnormally discharged from the printing cylinder with jamming effect, stop means to determine the normally disposed operative position of said stripping means, and means activated by engagement therewith of the normally disposed stripping means for controlling the operating power of the press, said latter means being operative to stop the press when disengaged by said stripping means.

3. In a printing press having side frames and a printing

cylinder journaled in and between the same, a stripping device cooperative with said printing cylinder comprising a bridge plate adjacently disposed along the discharge side of the latter and having peeler blade means dependent therefrom to engage the leading end of printed material issuing therefrom, whereby to inhibit adherence of said material to said printing cylinder and thus normally compelling said material to advance along the plane of the paper line of the press, carrier members pivoted substantially at the axis of the printing cylinder by which the bridge plate with its peeler blade means is movably supported, whereby the same can yield to up-thrusting pressure of printed materials abnormally discharged from the printing cylinder with jamming effect, and whereby the same can be manually displaced to give access to jamming material for removal thereof, and said carrier members and press side frames having cooperative stop means to determine the normally disposed operative position of the bridge plate and its peeler blade means.

20 4. In a printing press according to claim 3 including means to counterbalance the weight of the stripping device.

5. In a printing press according to claim 3 wherein the peeler blade means comprises a plurality of peeler blades, and said peeler blades and the bridge plate having cooperative means for adjustably and releaseably coupling the former to the latter in selected spaced apart relation.

25 6. In a printing press according to claim 5 including means to counterbalance the weight of the stripping device.

30 7. In a printing press having side frames and a printing cylinder journaled in and between the same, a stripping device cooperative with said printing cylinder comprising a bridge plate adjacently disposed along the discharge side of the latter and having peeler blade means dependent therefrom to engage the leading end of printed material issuing therefrom, whereby to inhibit adherence of said material to said printing cylinder and thus normally compelling said material to advance along the plane of the paper line of the press, carrier members pivoted substantially at the axis of the printing cylinder by which the bridge plate with its peeler blade means is movably supported, whereby the same can yield to up-thrusting pressure of printed material abnormally discharged from the printing cylinder with jamming effect, said carrier members and press side frames having cooperative stop means to determine the normally disposed operative position of the bridge plate and its peeler blade means, an electric press power control switch mounted on a press side frame, and an adjacent carrier member of the stripping device having means to engage and close the switch while the stripping device occupies its normally disposed operative position whereby to maintain operation of the press, said switch being adapted to open and stop the press when disengaged by said latter means due to upward displacement of the stripping device from its normally disposed operative position.

35 8. In a printing press according to claim 7 including means to counterbalance the weight of the stripping device.

50 9. In a printing press according to claim 7 wherein the peeler blade means comprises a plurality of peeler blades, and said peeler blades and the bridge plate having cooperative means for adjustably and releaseably coupling the former to the latter in selected spaced apart relation.

55 10. In a printing press according to claim 9 including means to counterbalance the weight of the stripping device.
